CLAIM

The ornamental design for a muzzle brake, as shown and described.

DESCRIPTION

FIG. 1 is a top, front, right perspective view of a muzzle brake according to the present disclosure.

FIG. 2 is a top, back, right perspective view of the muzzle brake of FIG. 1.

FIG. 3 is a bottom, front, left perspective view of the muzzle brake of FIG. 1.

FIG. 4 is a bottom, back, right perspective view of the muzzle brake of FIG. 1.

FIG. 5 is a right side view of the muzzle brake of FIG. 1.

FIG. 6 is a left side view of the muzzle brake of FIG. 1.

FIG. 7 is a top view of the muzzle brake of FIG. 1.

FIG. 8 is a bottom view of the muzzle brake of FIG. 1.

FIG. 9 is a front view of the muzzle brake of FIG. 1; and,

FIG. 10 is a back view of the muzzle brake of FIG. 1.

The broken lines in the Figures illustrate portions of the article that form no part of the claimed design.
